UNITED STATES PATENT OFFICE

104,735

DESIGN FOR A BOTTLE OR SIMILAR ARTICLE

Charles H. Ziff and Louis S. Getz, Chicago, Ill.

Application April 19, 1937, Serial No. 68,874

Term of patent 7 years

To all whom it may concern:

Be it known that we, Charles H. Ziff and Louis S. Getz, citizens of the United States, and residing in the city of Chicago, in the county of Cook and State of Illinois, have invented a new, original, and ornamental Design for a Bottle or Similar Article, of which the following is the specification, reference being had to the accompanying drawing forming a part thereof.

On the drawing:

Fig. 1 is a side elevational view of the bottle showing our new design.

Fig. 2 is a cross sectional view taken on line 2—2 of Fig. 1.

The side of the bottle opposite to that shown in the drawing is of substantially the same appearance and design as the side shown in Fig. 1.

We claim:

The ornamental design for a bottle or similar article, substantially as shown and described.

CHAS. H. ZIFF.
LOUIS S. GETZ.
